CATHODE-RAY OSCILLOGRAPH

Max Knoll, Berlin-Charlottenburg, Germany, assignor to Radio Corporation of America, New York, N. Y., a corporation of Delaware

Original application February 5, 1935, Serial No. 5,136, now Patent No. 2,152,487, dated March 28, 1939. Divided and this application June 7, 1937, Serial No. 146,967. In Germany December 12, 1928.

3 Claims. (Cl. 250—27)

This invention has for its object improvements in cathode-ray oscilloscopes, and is a division of Patent No. 2,152,487, issued March 28, 1939, and relates in subject matter to application, Serial No. 5,136, dated February 5, 1935.

More particularly, this invention relates to a new method and means for electrostatically focusing a beam of electrons in a cathode ray tube.

In describing the invention, reference will be made to the drawing, in which is shown a cathode ray tube embodying the invention connected in a circuit for automatically starting electron flow in response to transmission line surges by way of example.

The tube 32 for auto-electronic discharge shown in the drawing contains an anode 33 and an intercepting electrode (auxiliary anode) 34 which during the release of the beam functions as an anode. The release is effected by two spark gaps or glow-lamps 35 and 36 connected by way of windings 37, 38 with the perforated intercepting electrode 34 and by way of a high resistance element 39 with the cold cathode 40. The high-tension continuous current required for feeding the tube is generated in the known manner by means of transformer 41, valve 42, and condenser 43. If the gaps 35 and 36 are properly adjusted, any sudden surge of voltage arising from the transmission line or antenna 44 and inducted from the winding 45 according to the polarity of the surge, either onto the winding 37 or 38, causes a sparking of the gap 35 or 36, the duration of which depends upon the value of the capacity 46 and the resistance 47. By this the electrode 34, which has hitherto intercepted the beam, becomes an anode, and the extremely sharp point of the cathode 40 ejects an electronic beam through the perforations in the electrodes 34 and 33, the intensity of the beam can further be varied by means of the controlling electrode 33 by varying the angle of the cone-shaped electronic beam.

The focussing of the electron rays as required for the oscilloscope according to the present invention, can be effected in the known manner e. g. by magnetic fields. A new arrangement, especially convenient for the purpose in view, based on electrostatic effect, consists in fixing, at certain intervals from one another, co-axially with, and symmetrically to, the electronic beam ejected by the cathode, pairs of electrodes of suitable form (e. g. alternately perforated metal cylinders with small, and washers with large, diameter), which are connected alternately with appropriate voltages. In this way there are produced diver-

gent electric fields with a stress acting obliquely to the direction of the beam, in such a way as to compress the beam radially. If the voltage is sufficiently high, one single pair of electrodes may suffice to effect this concentration. The divergent fields can be obtained by various types of electrode. If a controlling voltage is supplied to such a device, the intensity of the electrons in the beam, and thereby the intensity of the focal spot, can be varied without inertia. The special advantages of this arrangement are: ease in construction and mounting, small weight, small dimensions, and avoidance of consumption of current.

With the alternate voltage connections made such that all the cylinders will be positive and all the washers negative, a series of divergent electric fields acting to compress the beam may be produced without necessity for progressively increasing voltages on the electrodes. In fact alternate electrodes may have the same polarity regardless of their number and their position in the series, as indicated in Fig. 6, which makes it possible to connect them in multiple, thus simplifying the wiring and insulation problems. Another advantage is that focusing may be accomplished without undue increase in velocity or "hardness" of the beam which latter would tend to render the beam less sensitive to deflection control. It will also be clear from Fig. 6 that this method of focusing also permits variation of the intensity of the electrons in the beam and thereby the intensity of the focal spot without undue disturbance of the focus, such variation being accomplished by supplying a controlling voltage to the focusing device as above mentioned, variations in the controlling voltage acting to correspondingly vary the forces exerted radially on the cathode-ray and consequently the density of the electrons within the focal spot. Any known or other suitable method of applying the controlling voltage may be used.

In the lower part of the figure is shown schematically an electrostatic device for concentrating the electronic beam in accordance with the method above described. It consists of relatively narrow cylindrical metal tubes 48 of substantially uniform diameter from end to end, sustained by supports 49 in such a position as to allow of the electronic beam to pass freely through them, and of the metal ring washers 50 of relatively large inside diameter between the tubes 48. If the washers 50 are charged negatively to the tubes 48, divergent electric fields are formed, which exercises a force concentrat-

ing radially the beam. Thus an exceptionally minute focal spot is obtained.

What I claim is:

1. In a cathode ray device, an electron emitting cathode and an anode member for producing a beam of electron rays, a target element, and means intermediate the cathode and the target for concentrating the electronic beam, said concentrating means comprising alternate metal tubes and ring washers arranged in sequence concentric with the beam, each tube spaced longitudinally from a preceding washer and each washer spaced longitudinally from a preceding tube axially of the beam, said tubes having an inside diameter smaller than the inside diameter of said washers, and means for maintaining the washers charged negatively to the tubes to form a sequence of alternate oppositely polarized divergent electric fields.
2. In a cathode ray device, a cathode and an anode for producing a beam of electrons, means in addition to the anode situated in the path of the beam beyond the anode for concentrating the electronic beam in a focal spot comprising

a tube and a ring washer longitudinally spaced in the tube, the ring washer having an inner diameter larger than the inner diameter of the tube and arranged coaxially with the beam, means for applying a voltage between the washer and the tube for maintaining the washer charged negatively with respect to the tube to form a divergent electric field. 5

3. Means for producing a focussed cathode ray beam comprising means for producing a cathode beam and focussing means in the path of the beam separate from and beyond the beam producing means comprising a plurality of annular conductors of which at least one extends longitudinally of the beam axis for a length at least 15 greater than the inner diameter of the annulus, each of said conductors being longitudinally spaced from an adjacent conductor on each side axially of the beam, and means for maintaining a difference of potential of alternate polarity between said conductors to produce alternate decelerating and accelerating electrostatic fields. 20

MAX KNOLL.
